CLAIM

The ornamental design for a lighting fixture, as shown and described.

DESCRIPTION

FIG. 1 is a perspective view of a lighting fixture comprising the new design;

FIG. 2 is a front elevational view thereof;

FIG. 3 is a right side elevational view thereof, a left side elevational view being a mirror image thereof;

FIG. 4 is bottom view thereof;

FIG. 5 is a perspective view of the lighting fixture configured as a pendant;

FIG. 6 is a perspective view of the lighting fixture configured as a chandelier; and,

FIG. 7 is a perspective view of the lighting fixture configured as a wall sconce.

The broken lines in the figures are for illustration purposes only and form no part of the claimed invention.
